SHIPPING CRATE

Filed Oct. 7, 1930

UNITED STATES PATENT OFFICE

PHILIP N. CURTIS, OF WORCESTER, MASSACHUSETTS, ASSIGNOR TO BAKER BOX COMPANY, OF WORCESTER, MASSACHUSETTS, A CORPORATION OF MASSACHUSETTS

SHIPPING CRATE

Application filed October 7, 1930. Serial No. 487,014.

This invention relates to a crate for holding and transporting milk bottles and other similar containers.

It is the object of my invention to provide an improved construction of crate for such purposes, so designed that the crate may be easily and economically manufactured and that it will most effectively serve its intended purposes.

With this and other objects in view, important features of the invention relate to the provision of an improved partition structure and improved means for securing the partition structure in place.

I also provide a construction which permits removal and replacement of the lower portion of the crate when this lower portion becomes worn or broken in service.

My invention further relates to arrangements and combinations of parts which will be hereinafter described and more particularly pointed out in the appended claim.

A preferred form of the invention is shown in the drawing, in which

Fig. 1 is a plan view of my improved crate;

Fig. 2 is a sectional elevation thereof, taken along the line 2—2 in Fig. 1;

Fig. 3 is a detail sectional view, taken along the line 3—3 in Fig. 1;

Fig. 4 is a sectional elevation, taken along the line 4—4 in Fig. 1; and

Fig. 5 is an enlarged fragmentary perspective view of a portion of the partition structure.

Referring to the drawing, my improved shipping crate comprises a casing formed of sides 10 and ends 11, and a partition structure comprising a set of relatively wide cross members 12 and a second set of relatively narrow and spaced cross members 13.

The sides 10 and ends 11 are secured together to form a rigid enclosing casing by inner and outer corner pieces 15 and 16. The lower portions 10^a and 11^a (Figs. 3 and 4) of the sides 10 and ends 11 are preferably formed separate from the upper portions of the members 10 and 11 but are secured in assembled relation therewith by the corner pieces 15 and 16.

The outer corner pieces 16 are preferably

provided with inwardly projecting end portions 17 (Fig. 1), adapted to be received in vertical grooves in the outer faces of the sides 10 and ends 11. When positioned in assembled relation, the corner pieces 16 thus effectively prevent spreading of the casing at the corners. The corner pieces are secured in position in any convenient manner but preferably by screws or rivets 20 extending through the parts of the casing and joining the inner and outer corner pieces together.

The partition structure is preferably formed as indicated in Fig. 5 which shows that the wide cross members 12 are notched, as indicated at 30, to receive the narrow cross members 13 in spaced relation. The members 13 are also preferably grooved in their side faces, as indicated at 32, to receive the edge portions of the members 12 and thus hold the members 12 from movement longitudinally of the members 13.

The members 12 and 13 are preferably formed of wood, which is particularly adapted for separating and securely holding glass containers such as milk bottles. The bottles are cushioned against the slightly yielding surface of the wood, and furthermore the partitions 12 and 13 subdivide the space within the crate in such a manner that circulation of air is reduced and the cool temperature of the bottles is more effectively maintained.

The inner faces of the sides 10 and ends 11 are grooved out for a portion of their width, as indicated at 35 in Fig. 2, and the ends of the members 12 and 13 are received and securely held in the grooves 35.

Tie rods 40 extend from side to side of the casing, and the ends of the cross rods are firmly secured in the sides 10 of the casing, preferably by being headed over against washers 41 at the outside of the casing, as indicated at Fig. 3.

The tie rods 40 are thus firmly secured in position and prevent spreading of the sides 10, firmly retaining the partition structure in the grooves 35. The bottom edges of the partition structure preferably rest directly on the tie rods 40, as indicated in Fig. 4, and the partition structure is thus firmly supported thereby.

The tie rods 40 also form the bottom of the crate and support the bottles or containers placed in the several compartments thereof. The rods 40 are upwardly spaced from the lower edge of the casing, as indicated in Fig. 3, thus providing a space to receive the projecting upper ends 44 of the inner corner pieces 15, by which means the crates may be securely stacked in superposed position.

10 In assembling my improved crates, the partition structure is preferably built up to form a unit, around which the ends and sides are then assembled and secured by the corner pieces 15 and 16. Or preferably two ends and one side are assembled, after which the partition structure is inserted and the second side is then placed in position.

15 It will be obvious that the bottom portions of the crate will receive the greatest amount of wear and will require the most frequent replacement. With my improved construction, by removing the lower fastening members 20, I can remove the bottom sections 10^a and 11^a of the sides and ends, together with the tie rods, and can replace the same without disturbing the upper portions of the casing or the partition structure mounted therein. The useful life of the crates is thus indefinitely extended.

20 Having thus described my invention and the advantages thereof, I do not wish to be limited to the details herein disclosed, otherwise than as set forth in the claim, but what I claim is:

25 30 A shipping crate comprising a rectangular side wall casing formed in upper and lower sections, a multi-cell partition structure secured within said casing, a bottom for said crate secured to said lower casing section and upwardly spaced from the lower edge thereof, and means to secure said upper and lower casing sections together, said lower casing section comprising side and end wall portions and being free from direct attachment to said partition structure and said lower casing section and bottom being removable and replaceable as a unit in said crate.

40 45 In testimony whereof I have hereunto affixed my signature.

PHILIP N. CURTIS.
